ABSTRACT: An improved cobalt-60 teletherapy source in which at least a portion of the necessary shielding material is included within the source container. High-activity cobalt-60 material is enclosed within a ring or cup-shaped shielding member within a double-walled stainless steel encapsulating container. The exterior dimensions of this container are such as to fit within a source capsule holder. Preferably, the internal shield in intimate contact with the cobalt-60 has a wall thickness of from about 0.3 to about 0.7 centimeters and comprises uranium or tungsten metal or an alloy thereof. This arrangement permits the use of higher activity cobalt loadings in standard teletherapy machines. Also, this permits more effective use of the radiation and more accurate and effective radiation therapy.

INTERNAL SHIELDED TELETHERAPY SOURCE

BACKGROUND OF THE INVENTION

Various types of high-energy radiation have been used for some time in the treatment of certain forms of cancer. Originally, radium was used in the form of implants and contact molds. Attempts to use radium in a teletherapy mode, that is, utilizing collimated radiation from a radium source spaced from the patient's skin were largely unsuccessful due to the low energy of the radium sources which gave a high-surface dose and a low-depth dose. In addition, because of the low specific activity of the radium salt, the sources were large and as a result the edges of the radium beam were ill defined. Because of these problems, X-rays became generally preferred in beam therapy. Ideally, the object of external-beam therapy is to produce a homogeneous distribution of absorbed energy within a prescribed treatment volume and time interval, while producing no energy absorption in the tissues outside this volume. It has been found that the higher the generating voltage, the more therapeutically useful are the characteristics of an X-ray beam for the treatment of deep-seeded cancer. Thus, X-ray generators with ever higher voltages have been developed.

In the early 1950's it was found that gamma radiation emitted by the decay of cobalt-60 is in the very desirable high-energy region and has certain other advantages over X-radiation. Teletherapy using cobalt-60 sources has a great number of advantages over prior radium and X-ray teletherapy. The attenuation of its high energy (1.25 Mev.) radiation as it passes through an absorbing medium is not as rapid as that of radiation of lower energies. As a result, the decrease in dose rate with increasing depth in tissue is more gradual with cobalt-60 radiation than with lower voltage X-radiation or radium-radiation beams.

Cobalt occurs in nature in one isotopic form, with a mass number of 59. Cobalt-60 can readily be produced by neutron irradiation of cobalt-59 in a nuclear reactor. The specific activity in curies of cobalt-60 per gram of the irradiated cobalt is dependent upon the thermal neutron flux to which the material is subjected in the reactor. Where the neutron flux is relatively low the specific activity of the cobalt-60 produced will be relatively low and a large quantity of the material will be required to give effective performance in a teletherapy source. For a variety of reasons, further discussed below, it is highly desirable that the cobalt-60 teletherapy source have relatively high specific activity.

An important advantage of cobalt-60 radiation is the fact that the point of maximum energy absorption for a single beam of cobalt-60 radiation is at a depth of approximately 0.5 centimeters beneath the skin rather than at the skin surface. Skin reactions are therefore minimal, even when radical doses are delivered.

At conventional X-ray energies, because of the predominance of absorption by the photoelectric process the energy absorbed in bone is significantly greater than that in soft tissue. At the energy of cobalt-60 radiation the principle absorption process is that of the Compton effect, for which the energy absorbed per roentgen per gram of bone and soft tissue is approximately the same. This reduces bone damage when the treatment traverses normal bone.

Since all body structures absorb cobalt-60 radiation to approximately the same degree, discontinuities in dosage patterns are minimized so that therapeutic dosimetry is more accurate. Scattered radiation arising from interaction of cobalt-60 primary radiation with tissue is predominantly in the forward direction. Because of the small amount of side-scattered radiation, the falloff of dose at the geometrical edge of the gamma-ray beam is rapid, reducing the dose to adjacent sensitive structures.

Cobalt-60 units are also advantageous over high voltage X-ray generators because of their simplicity, flexibility and constancy of output. The absence of complicated electric and electronic circuits reduces maintenance problems and

5 eliminates the need of a highly skilled maintenance staff. The relative simplicity and small size of the source head and the absence of heavy electrical connections allow a high degree of flexibility in equipment design. This has resulted in the development and production of a wide range rotational cobalt-60 units.

10 The radiation source used in the cobalt-60 teletherapy units consists of a small amount of cobalt-60 in a container which is inserted in the teletherapy head. The usual cobalt-60 beam therapy unit consists of the encapsulated cobalt-60 radioactive source, a source shield or housing, a shutter device to turn the useful beam on and off and a variety of support mechanisms and beam control and adjustment mechanisms. The source housing and shutter includes sufficient shielding material, such as lead, so that the leakage radiation from the source shield will average less than 2 milliroentgens per hour at a distance of one meter from the source in all directions. While a wide variety of therapy units have been designed, a 15 single international standard source holder has been designed which will fit most of these units. This holder can accommodate a cylindrical source up to 3 centimeters in diameter by 3 centimeters high. The quantity of shielding material included in the unit housing is determined by the radiation leakage limit and the expected activity of sources to be used therein. Thus, higher output sources may not be usable in older teletherapy units since they would cause leakage radiation exceeding the permissible limits. However, high-output source materials are now becoming available due to improved 20 ability to produce cobalt-60 in high flux level nuclear reactors. High activity sources permit the treatment of a deep seated tissue in shorter periods.

25 In the international standard source holder, the maximum source diameter is 3 centimeters. Of course, smaller diameter sources may be used by inserting a spacer ring (or shim) between the outer wall of the source and the inner wall of the holder. In general, it is desirable to have the smallest possible diameter source. As the source diameter approaches a true 30 point source and a diaphragm is used between the source and the object receiving the radiation, radiation will fall off sharply at the edge of the field. However, where the source has a large diameter, a large penumbra will result; that is, the radiation falloff outside the field will be more gradual. This results from the fact that radiation coming from one side of the source is 35 limited by the diaphragm aperture in a different way than that emerging from the opposite side. An extensive penumbra is undesirable since it will result in the irradiation of healthy and possibly sensitive tissues adjacent the portion being treated.

40 Thus, there is a continuing need for improved cobalt-60 teletherapy source configurations which permit the use of higher specific activity source materials without exceeding 45 permissible leakage radiation and which improve the accuracy and precision of the therapeutic radiation.

SUMMARY OF THE INVENTION

55 It is, therefore, an object of this invention to provide a teletherapy source overcoming the above-noted problems.

60 Another object of this invention is to provide a cobalt-60 teletherapy source permitting the use of higher output sources in existing machines.

65 Still another object of this invention is to provide a teletherapy source permitting a more precise radiation beam.

70 Still another object of this invention is to provide a teletherapy source of improved convenience, reliability and safety.

75 The above objects and others are accomplished in accordance with this invention by providing a cobalt-60 teletherapy source in which the cobalt-60 source material is at least partially surrounded by and in intimate contact with a quantity of shield material which is in turn doubly encapsulated in stainless steel containers, the outside dimension of which fits within the international standard teletherapy source holder. Preferably, the cobalt-60 material is in the form of

small pellets in a generally cylindrical array within a ring, ring-and-cap, or cup-shaped shield member. The radial walls of said shield member preferably have a thickness of from about 0.3 to about 0.7 centimeters. This thickness range is preferred since much thinner walls tend to decrease the shielding capability to the point where higher output cobalt-60 sources cannot be safely used while much thicker walls would decrease the diameter of the core to the point where unachievably high specific activity would be required in the source material. The internal shield member and source material are then doubly encapsulated in stainless steel cans having a thickness of about 0.65 millimeters. Stainless steel is preferred for the encapsulating cans because of its strength, corrosion resistance and ability to be easily closed with high integrity welds. It is undesirable to use a high-density material for the encapsulating container, since this would also attenuate the radiation in the treatment beam.

While any material having a density greater than about 10 grams per cubic centimeter would be useful in the internal shield member, unalloyed and unclad uranium metal or a suitable tungsten alloy are preferred for use in the internal shield. Uranium performs extremely well as the internal shield. Preferably, the uranium is unalloyed and unclad since any alloying or cladding materials would have lower densities and would decrease the shielding ability of the internal shield member. Applicants have found that uranium in the unclad state may be used in the configuration of this invention since the internal shield material is entirely encapsulated. Uranium metal is difficult to use in an external shield in air since it is easily oxidized and then expands in volume. Thus, an external uranium shield may expand to the point where it prevents disassembly of close-fitting components. Tungsten is also preferred for the internal shield material because of its high density and its availability at reasonable cost.

It has been found that the addition of the internal shield member made up of very effective shielding material in intimate contact with the source material is much more effective than the equivalent quantity of shielding material spaced further from the source material. The mass of shielding material to give an equivalent shield thickness is smaller where the shield is contained within the source material encapsulating cans than where the shield material is in the form of a ring outside the encapsulating cans. Also, the larger external shield ring would permit a greater quantity of radiation to leak out of the ends of the ring. Where the shielding is internal, the end leakage beams are significantly narrower.

The attenuation of gamma radiation through matter is exponential in that for a particular radiation energy successive equal thicknesses of a material will reduce the radiation intensity by equal fractions. For example, a 1.2 centimeter thickness of lead attenuates primary cobalt-60 radiation by a factor of 2, while an additional 1.2 centimeter will reduce the original exposure by a total reduction factor of 4. Thus, if it is required that the exposure dose rate be reduced by a factor of 1.000 in order to reduce the radiation leakage adjacent a therapy unit to permissible limits, then, since $1024=2^{\text{power}}$, a thickness of 12 centimeters of lead will be necessary for primary beam protection. The thickness of an absorber which attenuates a beam of radiation by one-half is called the "half-value thickness." For primary cobalt-60 radiation the half-value thickness of uranium is 0.566 centimeters and of tungsten is 0.69 centimeters. Thus, the inclusion of a 0.3 to 0.7 centimeter internal shield of uranium in a source capsule will increase the effective shielding of the overall unit by a factor of about 0.53 to 1.25. For tungsten this factor is about 0.43 to 1.02. Thus, with the teletherapy source of this invention, the permissible activity level of the source in a conventional teletherapy machine will be increased by from about 40 percent to about 125 percent.

As the use of the internal shield permits the use of higher activity materials, the source may be made narrower in order to approach more nearly to the ideal point source. This will greatly decrease the penumbra effect and substantially

decrease the undesired irradiation of sensitive structures adjacent to the matter being irradiated.

BRIEF DESCRIPTION OF THE DRAWINGS

5 Details of the invention and of preferred embodiments thereof will be further understood upon reference to the drawing, wherein:

10 FIG. 1 shows an isometric view, partly cut away, of a teletherapy source according to this invention positioned in an international standard source holder;

15 FIG. 2 shows an isometric view, partially cut away, of a second embodiment of the teletherapy source of this invention positioned in an international standard source holder; and

20 FIG. 3 shows a schematic representation of a typical cobalt-60 teletherapy machine including the teletherapy source of this invention.

DETAILED DESCRIPTION OF THE INVENTION

25 Referring now to FIG. 1 there is seen a teletherapy source generally designated 10 enclosed within an international standard source holder generally designated 11. The dimensions of source holder 11 have been made standard by international agreement. Source holder 11 carries external threads 12 to permit the source holder to be threaded into a teletherapy machine. Source holder 11 is loaded by inserting the cylindrical source 10 into the standard diameter bore of source holder 11. An annular inwardly projecting lip 13 prevents source 10 passing through the bore. A retaining ring 14 engaged in an annular slot in the bore of source holder 11 retains source 10 in position.

30 As seen in FIG. 1, source 10 consists of a quantity of cobalt-60 source material 15 within a ring-shaped internal shield member 16 both of which are doubly encapsulated within two concentric stainless steel cans 17 and 18. The end members of cans 16 and 17 are welded in place to prevent leakage of radioactive material.

35 This configuration permits the use of a high-activity cobalt-60 source material in a standard teletherapy machine since additional shielding material is provided in the most effective location. Also, the cylinder of cobalt-60 source material is relatively narrow thus decreasing the exit beam diameter and, therefore, the undesirable penumbra effect. Since the internal shielding material 16 is entirely enclosed within double-encapsulating cans 17 and 18, materials such as uranium metal which tend to swell when exposed to the atmosphere may be used without inconvenience. If an attempt were made to use a ring of uranium metal between a narrow source cylinder and the internal wall of source holder 11, over a period of time the uranium would swell making removal of the shielding and source material from the source holder difficult, if not impossible. Also, the use of shielding material between the external wall of the source and the internal wall of the source holder would be difficult since the international standard source holder has no provision for retaining such an assembly in position. Further, a greater amount of the relatively expensive shielding material would be required to give the desired thickness if the shielding material were interposed between the outer wall of the source and the inner wall of the source holder instead of within the source cans as provided in the teletherapy source of this invention.

40 FIG. 2 shows a second embodiment of the teletherapy source of this invention. As in FIG. 1, the source 10 is retained between a lip 13 and a retaining ring 14 within the international standard source holder 11. However, in this instance the internal shield member 16' has a generally cylindrical ring-and-cap or cup-shaped configuration rather than the ring-shape shown in FIG. 1. The configuration shown in FIG. 2 will be preferred where source activity is very high. The internal shield member 16' provides additional shielding both at the sides of source material 15' and at the back of the source. Of course, shielding in the beam port region would be undesirable since this would interfere with the use of the source in ir-

radiating objects. Also, where the specific activity of the source material is very high, and the diameter of the cylinder of source material is relatively narrow, the portion of source material at the end of the source material cylinder away from the beam port will tend to be self-shielded by the source material closer to the beam port. Therefore, adding additional shielding material in the form of a cap or cup base at the back of the source in place of a portion of source material will not significantly decrease the effectiveness of a very high-activity source material while significantly increasing the shield effectiveness in this direction.

FIG. 3 shows a schematic representation of a typical teletherapy machine in which the teletherapy source of this invention is especially useful. The teletherapy head generally designated 20 is positioned above the object 21 to be irradiated on any conventional supporting structure (not shown). A generally cylindrical shutter drum 22 is positioned in a horizontal cylindrical opening throughhead 20. Drum 22 is rotatable by a drive means 23. Adjacent one edge of drum 22 is a horizontal opening within which source drawer 24 is slidably inserted. Drawer 24 is held in place by a removable end cover 25. The teletherapy source in source holder 11 may be directly inserted into a cavity in drawer 24, or the cavity may be sized and threaded to receive teletherapy source in source holder 11 in source drawer 24. Drive means 23 is capable of rotating drum 22 from an "off" position as shown, in solid lines in FIG. 3, in which the source is surrounded by shielding material to an "on" position (shown in broken lines) in which the source in source holder 11 is adjacent a port 26 which permits radiation of object 21.

Collimating blocks 26 are provided to adjust the width of the irradiation beam, which is indicated by lines 27. As can be seen from FIG. 3, where the source in source holder 11 is a point source, line 17 will outline a sharp, distinct area on object 21. Where the source in source holder 11 has an appreciable source diameter, it is apparent that the edges of the area outlined by lines 27 will be vague and indistinct, thus making the treatment of a distinct zone on object 21 difficult.

As is apparent in FIG. 3, when the source is in the "off" position, a large mass of shielding material 28 has been installed in head 20 adjacent the open or beam port end of the source holder. However, since the physical dimensions of drawer 24 and of drum 22 behind source holder 11 are fixed, it is difficult to add shielding at the sides and/or back of the source material where it is desired to use higher activity sources than those for which the source head was originally designed. Thus, Applicants' internal shielding concept will permit a substantial increase in the capabilities of commercial teletherapy machines.

Although specific components and proportions have been described above, other materials as indicated above, may be used with similar results where suitable. In addition, other materials may be added to the source material, shielding material, etc. to enhance or otherwise modify their properties.

Other modifications and applications of the present invention will occur to those skilled in the art upon reading the

present disclosure. These are intended to be included within the scope of this invention.

We claim:

1. A teletherapy source comprising:
  - a. a quantity of high specific activity cobalt-60 teletherapy source material in generally cylindrical configuration;
  - b. a quantity of a shielding material having a density greater than about 10 grams per cubic centimeter at least partially surrounding and in intimate contact with said source material;
  - c. a first closed stainless steel container surrounding said source material and shielding material; and
  - d. a second closed stainless steel container surrounding said first stainless steel container.
15. 2. The teletherapy source according to claim 1 wherein said cobalt-60 source material has a specific activity of from about 300 to about 500 curies per gram.
20. 3. The teletherapy source according to claim 1 wherein said shielding material is generally ring shaped and has a wall thickness of from about 0.3 to about 0.7 centimeters.
25. 4. The teletherapy source according to claim 1 wherein said shielding material is substantially cup shaped and has a substantially uniform thickness of from about 0.3 to about 0.7 centimeters.
30. 5. The teletherapy source according to claim 1 wherein each of said stainless steel containers has a wall thickness of about 0.65 millimeters.
35. 6. The teletherapy source according to claim 1 wherein said shielding material is selected from the group consisting of unalloyed, unclad uranium metal and tungsten alloys.
40. 7. In a cobalt-60 teletherapy source assembly comprising an annular international standard teletherapy source holder, secured within said holder a source capsule comprising a quantity of cobalt-60 teletherapy source material doubly encapsulated within stainless steel containers; the improvement wherein a quantity of a shielding material having a density greater than about 10 grams per cubic centimeter is provided between said cobalt-60 source material and said encapsulating containers, said shielding material at least partially surrounding and in intimate contact with said source material.
45. 8. The assembly according to claim 7 wherein said cobalt-60 source material has a generally cylindrical configuration and said shielding material is in the form of a ring-shaped member surrounding and in intimate contact with said source material and in contact with the inner wall of the smaller of said encapsulating containers, said shielding material being selected from the group consisting of tungsten alloys and unalloyed, unclad uranium metal, said ring-shaped member having a wall thickness of from about 0.3 to about 0.7 centimeters.
50. 9. The assembly according to claim 7 wherein said shielding material is generally cylindrical with an axial opening in one end filled with said cobalt-60 source material, said shielding being material selected from the group consisting of unclad, unalloyed uranium metal and tungsten alloys, said shielding material having a substantially uniform wall thickness in the range of from about 0.3 to about 0.7 centimeters.
